UNITED STATES PATENT OFFICE.

HENRY A. KINARD, OF RINGGOLD, LOUISIANA.

DESIGN FOR A SHOW-CASE WHEEL.

SPECIFICATION forming part of Design No. 30,740, dated May 9, 1899.

Application filed April 11, 1899. Serial No. 712,671. Term of patent 7 years.

To all whom it may concern:

Be it known that I, HENRY A. KINARD, a citizen of the United States, residing at Ringgold, in the parish of Bienville and State of Louisiana, have invented and produced a new and original Design for a Show-Case Wheel, of which the following is a specification.

This invention relates to a new and original design for a show-case wheel; and it has for its object to provide a design of this character that shall be both useful and ornamental.

The leading feature of the design resides in a circular body having a circular series of open-top triangular compartments, a circular rim connecting the compartment-partitions at the upper outer edges thereof and having inwardly-projecting tongues alining with the partitions, and a peripheral series of rectangular transparent panels located between the rim and the base and arranged over the outer ends of the compartments.

The minor features of the design are the body having a circular base-piece at the bottom of the compartments, a circular center block disposed in the same horizontal plane as the circular rim and arranged at the inner upper edges of the compartment-partitions, and wedge-shaped pieces arranged upon opposite sides of each compartment-partition at the outer ends thereof.

An additional minor feature of the design is the circular body having a peripheral series of upright rectangular blocks, said blocks being arranged at the outer ends of the partitions and alternating with the transparent panels.

In the drawings, Figure 1 is a perspective view of a show-case wheel embodying the herein-described design. Fig. 2 is a plan view thereof. Fig. 3 is a vertical cross-sectional view on the line 3-3 of Fig. 2.

Referring to the accompanying drawings, the numeral 1 designates a circular body of a show-case wheel, which is provided with a circular base-piece 2, supporting thereon a

plurality of radially-disposed upright partitions 3, between which are formed a circular series of triangular open-top compartments 4. The upper outer edges of the compartment-partitions 3 are connected by a circular rim 5, arranged flush with the top edges of the partitions and provided at the inner peripheral edge thereof with a plurality of spaced inwardly-projecting tongues 6, each of said tongues 6 directly adjoining and alining with the compartment-partitions 3, contiguous thereto.

At the center of the circular body there is arranged a circular center block 7, which fits upon the inner upper edges of the radial partitions 3 and is disposed in the same horizontal plane as the circular rim 5, connecting the outer ends of the partitions. The upright partitions 3, separating the triangular compartments 4, have arranged upon the opposite sides of the same and at their outer ends wedge-shaped pieces 8, whereby each partition is provided at its outer end with a triangular enlargement, as plainly shown in Fig. 2 of the drawings.

In addition to the features pointed out the circular body of the wheel is provided with a peripheral series of rectangular transparent panels 9, located between the rim 5 and the base 2 and arranged over the outer ends of the triangular compartments, and at the outer ends of the partitions are arranged upright rectangular blocks 10, which alternate with the transparent panels 8 and complete the characteristic features of the design.

What is claimed is—

The design for a show-case wheel, herein shown and described.

In testimony that I claim the foregoing as my own I have hereto affixed my signature in the presence of two witnesses.

HENRY A. KINARD.
